UNITED STATES PATENT OFFICE.

CHARLES H. LEONARD, OF GRAND RAPIDS, MICHIGAN.

DESIGN FOR A GAME-BOARD.

SPECIFICATION forming part of Design No. 33,532, dated November 6, 1900.

Application filed September 7, 1900. Serial No. 29,349. Term of patent 7 years.

To all whom it may concern:

Be it known that I, CHARLES H. LEONARD, a citizen of the United States, residing at the city of Grand Rapids, in the county of Kent and State of Michigan, have invented a new and original Design for a Game-Board; and I do hereby declare that the following is a full, clear, and exact description of the same, which will enable others skilled in the art to which it appertains to make and use the same.

The design consists in the novel outline and configuration illustrated in the appended drawings, wherein like numerals of reference indicate corresponding parts throughout the several views thereof, and in which—

Figure 1 is a perspective view illustrating more particularly the upper side of the game-board, upon which is the playing-field. Fig. 2 shows a central view thereof.

○ The design consists of the square base 1, having upon its upper face 2 the outlines of an ordinary checker-field 3, with the alternate squares 4 thereof colored in a suitable man-

ner to identify them. At each of the four sides of the checker-field is a series of back-gammon-points 5, said points extending outwardly at right angles from the sides of the checker-field, and each of said points being triangular in form and having its base toward the margin of the checker-field proper. The points do not extend entirely across the upper face 2 of the base 1, between the edge of the checker-field and the rim 6, which surrounds the base 1.

Having thus fully described my invention, what I claim as new, and desire to secure by Letters Patent, is—

The design for a game-board as herein shown and described.

In testimony whereof I have hereunto set my hand in presence of two subscribing witnesses.

CHARLES H. LEONARD.

Witnesses:

EDWARD TAGGART,
JAMES B. DAVIES.
